X-RAY PROTECTIVE GLOVE

Larry Sternlicht, Brooklyn, N. Y.

Application September 24, 1940, Serial No. 358,089

3 Claims. (Cl. 250—108)

The invention relates to new and useful improvements in an X-ray protective glove.

More particularly the invention proposes a glove as mentioned which is characterized by a glove body having a leather casing and an interior lining, and the glove body to consist of a heavy sheet of rubber containing lead and having its seams constructed in a certain manner.

More specifically the invention proposes to so construct the seams as to prevent the passage of X-rays through the seams. Heretofore X-ray protective gloves have been made which included a glove body, a leather casing for the body and cloth material lining the body. However, in these prior constructions, sections of the glove body forming the seam were stitched together. This construction is defective in that the X-rays pass through the holes of the stitches and reach the hand of a person using the glove.

More specifically the invention contemplates so constructing each seam as to have overlapping edge portions arranged in such a way that X-rays coming straight at the glove could not possibly pass through the seam even though the seam is secured together with cement or material not capable in itself in stopping X-rays.

Still further the invention proposes to reinforce the seam with strips of rubber material containing lead in a way so as to make doubly sure that no X-rays can pass through the seam areas.

Still further the invention proposes a construction of a glove as mentioned which is simple and durable and which may be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of an X-ray protective glove constructed in accordance with this invention.

Fig. 2 is a fragmentary sectional view taken on the line 2—2 of Fig. 1.

Fig. 3 is a fragmentary sectional view taken on the line 3—3 of Fig. 1.

Fig. 4 is a fragmentary sectional view taken on the line 4—4 of Fig. 1.

Fig. 5 is a fragmentary enlarged sectional view of an area of the glove between a pair of adjacent fingers.

Fig. 6 is a developed view of the main glove body.

Fig. 7 is a developed view of a certain finger portion used in conjunction with Fig. 6.

Fig. 8 is a developed view of the thumb, used in conjunction with the main glove body shown in Fig. 6.

Fig. 9 is a developed view of the leather casing for the glove body.

Fig. 10 is a developed view of one of the side gussets used between the front and rear portions of the fingers of the glove body shown in Fig. 9.

Fig. 11 is a fragmentary sectional view similar to Fig. 3 but illustrating a modified construction.

Fig. 12 is another fragmentary sectional view similar to Fig. 3 but illustrating still another form of the invention.

Fig. 13 is another fragmentary sectional view similar to Fig. 3 but illustrating still another form of the invention.

Fig. 14 is a perspective view of a mitten glove constructed in accordance with this invention.

The X-ray protective glove in accordance with this invention includes a glove body 10, cloth material 11 lining the said cloth body 10, and a leather casing 12 engaged over the glove body. The said glove body 10 consists of heavy sheet of rubber containing lead which is known to stop X-rays. This glove body is formed from a heavy sheet of rubber impregnated with the lead in known ways. The glove body 10 has seams joining sections thereof. In Fig. 3 one of these seams is illustrated. Each seam comprises overlapping edge portions 10^a and 10^b arranged obliquely of the faces of the glove body. These overlapping sections are vulcanized. A strip of rubber tape material 14 containing lead is extended along and over the overlapping edge portions 10^a and 10^b and is vulcanized to these portions so as to reinforce the seam to add to its strength and also reinforce the seam in so far as the ability of X-rays to pass is concerned.

The glove body 10 may be constructed from various patterns and designs and still embody this invention. However, one form of construction is illustrated in Figs. 6 to 8 inclusive. In these figures the glove body is shown to be composed of sheet rubber material cut into a glove pattern having finger sections 15, 16, 17 and 18 representing the palm sides of the four fingers. This glove pattern has a central section 19 representing the palm side of the hand. The section 19 is formed with an opening 20 to receive the thumb as hereinafter more fully explained. The glove body is adapted to be folded along the

line AB. The section 21 to the left of this line represents the back section of the cloth. It is provided with a finger portion 15' complementary to the finger section 15. It is also provided with a finger section 18' complementary to the finger section 18.

The sections 15' and 18' are slightly wider than the corresponding finger sections 15 and 18 so that when the edge portions are secured together there will be a hollow formed in alignment with these sections. The section 21 is also provided with edge portions 16^a and 17^a to receive finger sections complementary to the finger sections 16 and 17. In Fig. 7 a finger section 16' is illustrated which is adapted to be mounted upon the edge section 16^a and to cooperate with the finger section 16 to form the glove body. Another similar section as shown in Fig. 7 is provided to represent the complementary back side of the finger section 17. In Fig. 8 a thumb piece 23 has been shown. This thumb piece is adapted to be folded along the line CD and the edges secured together and certain of the edges secured around the opening 20 as is customary in glove construction.

The important feature of constructing the glove from the parts shown in Figs. 6 to 8 inclusive, is that the edge portions forming the seams are constructed in accordance with this invention. Each of the edge portions is beveled, and connected together to overlap, as shown in Fig. 3. This construction holds true for the edges of the finger portions, as well as the edges of the body section of the glove.

In Fig. 2 a section has been illustrated of the body portion of the glove, and particular attention is called to the over-lapping edge portions 10^a and 10^b and the rubber tape strip 14. Fig. 3 represents a section on the line 3-3 showing the seam between the thumb of the glove and the body of the glove. Fig. 4 represents a section across one of the fingers of the glove. This section illustrates the way in which the back portion of the finger is wider than the palm portion so that the back portion must be arched to produce a hollow 24 into which the finger may engage. Particular attention is called to the edge seams of these sections. Each of these seams have overlapping portions 10^a and 10^b which are vulcanized together, and also have a strip of rubber tape 14 engaged over the overlapping edges and vulcanized in position. The overlapping edges 10^a and 10^b in Fig. 4 are extended in the same direction contrasted with the prior arrangement in Figs. 2 and 3 in which they are extended in the opposite directions. However, the principle is essentially the same. The tape 14 extends over the outer faces of these overlapping edge portions.

In Fig. 5 a detail of the seam between the finger portions of the glove has been illustrated. This seam is also provided with overlapping edge portions 10^a and 10^b and the usual rubber tape strip 14. However, this strip 14 at this particular location is cemented over the cloth material lining 11 of these sections. The strip 14 is very short, extending only from the palm portion of the glove to the back portion between the fingers.

In Fig. 9 a developed view has been illustrated of the main portion of the leather casing of the glove. It will be noted that the leather casing is formed from a sheet of leather cut according to a pattern so as to have a palm section 25 formed with an opening 26 into which the thumb portion may be set. This glove body also has a back section 27. It may be folded along the line

EF so as to superimpose the palm and back sections. The section 25 is provided with four finger portions 28, 29, 30 and 31. The section 27 is provided with four complementary finger sections 28', 29', 30' and 31'. The areas between adjacent edges of the finger sections are secured to gussets 32, such as illustrated in Fig. 10. This leather casing has its seams sewed together in the usual glove like fashion. This casing is formed just the same as the ordinary leather glove. It is forced upon the rubber glove body and maintains its position frictionally.

In Fig. 11 a modified form of the invention has been disclosed which distinguishes from the prior form in the construction of the seams. In this form of the invention each seam is shown to comprise interengaged edge sections 10^{aa} and 10^{bb}. These interengaged sections have inclined areas arranged obliquely to the faces of the glove so as to prevent the direct passage of X-ray through these seams. The usual rubber strip 14 is mounted across and vulcanized to the overlapping edge portions 10^{aa} and 10^{bb}. This glove is also provided with the cloth material lining 11 and with the leather casing 12.

In Fig. 12 another form of the invention has been disclosed which distinguishes from the previous form in the construction of the seam. In this form of the invention the seam is composed of adjacent edge portions 10^x and 10^y which have concaved complementary edges into which there is set a cylindrical strip of rubber material with lead 10^z. This cylindrical strip of rubber material fits into the concaved edges and the parts are vulcanized together and the construction is such that X-rays which travel in straight lines could not possibly pass through the seam. The usual rubber strip 14 is engaged over the adjacent edge portions 10^x and 10^y. The glove is also provided with a cloth lining 11, and with the leather casing 12.

In Fig. 13 still another form of the invention has been disclosed which is very similar to the form shown in Fig. 12 distinguishing merely in the formation of the recessed edges of the adjacent edge sections 10^{xx} and 10^{yy}, and in the shape of the filler strip 10^{zz}. In this particular form of the invention the filler strip 10^{zz} is substantially diamond shape in transverse cross sections and fits into complementary edge portions of the edges 10^{xx} and 10^{yy}. This construction is also such that X-rays traveling in straight lines could not possibly pass through the seam. The seam is reinforced with the rubber strip 14. This glove has the cloth material lining 11, and the leather casing 12, as previously explained.

In Fig. 14 a mitten type of glove 35 has been illustrated which has a thumb 36, an index finger 37 and a portion 38 for receiving the three other fingers. This glove is constructed in the same way as the gloves previously described. It is illustrated merely to point out that the invention may be embodied in different types and designs of gloves.

It is to be understood that the X-ray protective glove may be coated with a layer of rubber coating to produce a shiny finished surface. Gloves finished in this manner will not require an additional outer leather glove.

While I have illustrated and described the preferred embodiments of my invention, it is to be understood that I do not limit myself to the precise constructions herein disclosed and the right is reserved to all changes and modifications

coming within the scope of the invention as defined in the appended claims.

Having thus described my invention, what I claim as new, and desire to secure by United States Letters Patent is:

1. An X-ray protecting glove, comprising a glove body, cloth material lining said glove body, a leather casing engaged over said glove body, and said glove body consisting of a heavy sheet rubber containing lead and having seams joining sections thereof, each seam comprising recessed edge portions of said sections, and a rubber filler strip extended between said recessed edge portions and vulcanized thereto.

2. An X-ray protecting glove, comprising a glove body, cloth material lining said glove body, a leather casing engaged over said glove body, and said glove body consisting of a heavy sheet

rubber containing lead and having seams joining sections thereof, each seam comprising recessed edge portions of said sections, and a rubber filler strip extended between said recessed edge portions and vulcanized thereto, said filler strip being of cylindrical shape.

3. An X-ray protecting glove, comprising a glove body, cloth material lining said glove body, a leather casing engaged over said glove body, and said glove body consisting of a heavy sheet rubber containing lead and having seams joining sections thereof, each seam comprising recessed edge portions of said sections, and a rubber filler strip extended between said recessed edge portions and vulcanized thereto, said filler strip being of diamond shape in transverse cross section.

LARRY STERNLICHT.
